(57) **CLAIM**

The ornamental design for a carrying case for glucose monitors as shown and described.

DESCRIPTION

FIG. 1 is a front view of a carrying case for glucose monitors. The unshaded square within broken lines encloses an aperture.

FIG. 2 is a back view of the carrying case for glucose monitors of FIG. 1 thereof, with the top lid outside the case, the unshaded square within broken lines encloses an aperture;

FIG. 3 is a left view of the carrying case for glucose monitors of FIG. 2 thereof;

FIG. 4 is a right-side view of the carrying case for glucose monitors of FIG. 2 thereof;

FIG. 5 is a top view of the carrying case for glucose monitors of FIG. 2 thereof, the unshaded rectangular area encloses an aperture.

FIG. 6 is bottom view of the carrying case for glucose monitors of FIG. 1 thereof. The unshaded rectangular within broken lines encloses an aperture;

FIG. 7 is a right-side view of the carrying case for glucose monitors of FIG. 1 thereof, with the top lid open;

FIG. 8 is a left side view of the carrying case for glucose monitors of FIG. 7 thereof;

FIG. 9 is a front view of the carrying case for glucose monitors of FIG. 7 thereof, with the top lid open;

FIG. 10 is a back view of the carrying case for glucose monitors of FIG. 7 thereof, with the top lid open;

FIG. 11 is a back view of the carrying case for glucose monitors of FIG. 7 thereof, with the back clip rotated 90 degrees to a horizontal position; and,

FIG. 12 is a back view of the carrying case for glucose monitors of FIG. 7 thereof, with the back clip rotated an obtuse degree.

Broken lines in disclosure are for illustrative purposes of showing additional stitch lines form no part of the claimed design. The unshaded square or rectangular areas described in the above individual Figure descriptions enclose an aperture on the surface.
